UNITED STATES PATENT OFFICE.

OSCAR C. RIXSON, OF NEW ROCHELLE, NEW YORK.

DESIGN FOR A PAIR OF HINGE-KNUCKLES.

44,346.

Specification for Design.

Patented July 15, 1913.

Application filed August 9, 1912. Serial No. 714,313. Term of patent 14 years.

To all whom it may concern:

Be it known that I, OSCAR C. RIXSON, a citizen of the United States, and a resident of New Rochelle, county of Westchester, State of New York, (whose post-office address is No. 7 East Forty-second street, New York, N. Y.,) have invented a new, original, and ornamental Design for a Pair of Hinge-Knuckles, reference being had to the annexed drawings, in which—

Figure 1 is a plan view and Fig. 2 an elevation.

I claim:

The ornamental design for a pair of hinge-knuckles, as shown.

In testimony whereof I have signed this specification in the presence of two subscribing witnesses.

OSCAR C. RIXSON.

Witnesses:

C. A. L. MASSIE,
RALPH L. SCOTT.
